DEISTER MACHINE COMPANY, OF FORT WAYNE, INDIANA, A CORPORATION.

ORE-CONCENTRATOR.

1,335,824.

Specification of Letters Patent.

Patented Apr. 6, 1920.

Application filed September 10, 1919. Serial No. 322,915.

To all whom it may concern:

Be it known that we, EMIL DEISTER and WILLIAM F. DEISTER, citizens of the United States, residing at Fort Wayne, in the 5 county of Allen and State of Indiana, have invented new and useful Improvements in Ore-Concentrators, of which the following is a specification.

The invention relates to ore concentrators 10 and particularly to such concentrators which are differentially reciprocated and transversely inclined downwardly and adapted especially for treating materials usually treated on jigs.

15 The object of the invention is to provide a simple concentrating table which shall have large capacity and shall be highly efficient in operation and in delivering a finished product without the use of jigs and 20 cleaning-up tables. Other objects and advantages will be set forth hereinafter.

In the accompanying drawings we have illustrated the invention in simple form in which—

25 Figure 1 is a plan view of the deck of the table;

Fig. 2 a cross-sectional view on line 2—2 of Fig. 1;

30 Fig. 3 a cross-sectional view on line 3—3 of Fig. 1;

Fig. 4 a cross-sectional view on line 4—4 of Fig. 1;

Fig. 5 a cross-sectional view on line 5—5 of Fig. 1; and

35 Fig. 6 an enlarged view of a portion of the riffles.

Referring to the drawings, 10 indicates the deck of the table, 11 being the head or motion end of the deck, 12 the mineral discharge end, 13 the feed and dressing water side and 14 the tailings discharge side. Arrow 15 indicates the direction of differential reciprocation of the table. In the operating position of the deck it slopes transversely 40 downward from the feed side to the tailings discharge side, the slope being relatively steep. The surface of the deck is formed in three coterminous sections which extend transversely across the same, their coterminous lines or edges being oblique or diagonal to the line of reciprocation of the deck. Section $a b c d$ extends along the head end of the deck, along a portion of the feed side and along the greater portion of the tailings 45 discharge side of the deck. Section $c d e f$ is adjacent section $a b c d$ and extends from the feed side to the tailings discharge side of the deck and slopes upwardly from section $a b c d$ to section $e f g h$, the latter section extending along the mineral discharge 50 end of the deck and along the feed side from its juncture with section $c d e f$ to the mineral discharge edge. Sections $a b c d$ and $e f g h$ are substantially horizontal in operating position in the line of reciprocation 55 of the deck and section $e f g h$, the plateau, is elevated above section $a b c d$ with section $c d e f$ connecting them. Section $c d e f$ is substantially coincident at its forward corner with the corner of the table between the 60 tailings discharge side and the mineral discharge edge.

Riffles 16 are suitably secured to the deck over section $a b c d$ with their tips extending onto section $c d e f$. The lowest riffles 17 65 (two being illustrated) extend across sections $c d e f$ and $e f g h$ to the mineral discharge edge of the deck and riffles 18 next above riffles 17 extend to the rear edge of section $c d e f$. Riffles 16 are slightly tapered from dotted line 19 to their tips and each riffle 16 is cut away from its tip to a suitable point rearwardly of the tip, the cut-out portion being on the lower side of each riffle. The tapering of the riffles gradually 70 reduces their height from line 19 to their tips. A displacement riffle 20 is secured to the deck in each trough or channel 16^a and in contact with the lower side of each riffle 75. The forward end of each riffle 20 terminates on section $c d e f$ in the same diagonal line which passes through the tips of riffles 16, and the cut-out portions are provided in riffles 16 so that the forward ends of riffles 20 shall serve as additional riffles 80 on section $c d e f$ and substantially double the number of riffles on said section. All of the riffles are diagonal to the line of reciprocation of the table and also diagonal to the transverse axis of the table or to the 85 direction in which the materials fed onto the deck from feed box 21 will flow under the influence of gravity. 22 indicates the dressing water box.

In operation, the deck is adjusted with the 90 proper transverse inclination downwardly. The materials are deposited on the deck from the feed box and tend to flow transversely across the deck under the influence 95 of gravity. The heavier or coarser mate-

rials are caught by the riffles and the lighter materials pass over the same, more and more of the heavier materials being captured by the riffles in succession. The differential reciprocating movement of the table causes the materials caught by the riffles to be advanced in the troughs or channels toward the mineral discharge edge of the deck. The heavier materials will collect in the troughs adjacent the upper sides of the riffles and the lighter materials will lie over the heavier materials and extend to the lower sides of the riffles. As the materials are advanced in the troughs the lighter and finer materials reach the displacement riffles which elevate them so that they will be washed over to the riffles below, the washing-over action being progressive as the materials advance. The displacement riffles restrict the channels so that the waste materials must necessarily be forced out of the troughs in succession down the slope, more and more of the minerals being caught by the riffles and delivered to the mineral discharge edge of the table. The concentrates pass out from the tips of the riffles and travel down section *c d e f* in front of the riffle tips, riffles 18 causing them to pass onto the lower end of section *e f g h* from which they are delivered at the concentrates discharge edge of the deck. The wash water is deposited on sections *c d e f* and *e f g h* and flows down the slope toward the tailings discharge. The water meets the materials advancing in the troughs near the forward ends of the riffles and since the riffles are doubled in number along section *c d e f* the water has opportunity to wash out all gangue, which may be mixed with the concentrates, before the concentrates leave the riffle tips, the finer concentrates which may be washed over any riffle with the gangue being caught by a riffle below and the gangue passing off the table at the tailings discharge.

The riffle channels are relatively deep and wide rearwardly of the rear ends of riffles 20, while forwardly of said ends of said riffles 20 the channels are narrowed and gradually lessen in depth to the tips of the riffles. The diagonal arrangement of riffles is very effective in catching the minerals and as the tips of the riffles are above the rear ends of the riffles, relatively to the transverse axis of the deck, the minerals are compelled to travel in the channels up-hill, as it were, to the tips thereby affording effective work on the part of the wash water in cleaning up the minerals by washing the gangue or sands over the tapered riffles 16. The lowermost riffles 17 catch any of the fine minerals which pass over the riffles above them and conduct the same to the mineral discharge edge of the deck.

In Fig. 6 the construction of the riffles 16

is clearly shown, 16 indicating the main riffles and 20 the displacement riffles.

We prefer to use rubber as a covering for the deck of the table, as indicated in Figs. 3-5, since it resists injury by the coarse materials passing over it in greater degree than does linoleum and hence has longer life than linoleum or any other covering for concentrator decks. The riffles may also be formed of rubber since rubber has a longer life than wood where the feed is coarse.

What we claim is:

1. In a differentially reciprocating concentrating table the combination of a deck having a plurality of coterminous sections on its surface which in operating position are inclined downwardly from the feed side to the tailings discharge side of the deck, one of the sections being inclined upwardly with respect to the longitudinal axis of the table, a series of main riffles on the deck having their forward ends terminating on the upwardly inclined section, and a series of displacement riffles in the channels between the main riffles and abutting the lower sides of the main riffles and having their forward ends terminating on the upwardly inclined section, the forward portions of the main riffles being cut away to form channels between said riffles and the corresponding portions of the displacement riffles.

2. In a differentially reciprocating table having its deck transversely inclined downwardly, a series of main riffles on the deck and a series of displacement riffles between the main riffles and abutting the lower sides of the main riffles.

3. In a differentially reciprocating concentrating table a deck having its surface inclined downwardly from the feed side to the tailings discharge side of the deck, a series of main riffles on the deck and a series of displacement riffles between the main riffles and abutting the lower sides of the main riffles respectively, the forward portions of the main riffles being cut away on their lower sides to form channels between said riffles and the corresponding portions of the adjacent displacement riffles.

4. In a differentially reciprocating concentrating table a deck, a series of main riffles on the deck and a series of riffles between the main riffles and adjacent the lower sides of the main riffles respectively, the lower sides of the main riffles being cut away at their forward ends to form channels between the main riffles and the second series of riffles at said forward ends.

5. In a concentrating table a deck adapted to be differentially reciprocated, a series of main riffles on the deck extending from the feed side to the tailings discharge side of the deck and diagonally arranged with respect to the line of reciprocation of the deck and their forward ends terminating on a

line diagonal to said line of reciprocation, and a series of displacement riffles on the deck between the main riffles and abutting the sides of the main riffles which face the 5 tailings discharge side of the deck, the forward ends of the displacement riffles terminating on said diagonal line of the terminals of the main riffles and the main riffles being cut out at their forward ends to form channels 10 between the same and the displacement riffles adjacent thereto.

6. In a concentrating table a deck adapted to be reciprocated differentially, a series of main riffles on the deck having their forward ends terminating in a line diagonal to the line of reciprocation of the deck and being 15 tapered to gradually reduce the height

thereof for a portion of their length and a series of displacement riffles in the channels between the main riffles and abutting the 20 sides of the main riffles which face the tailings discharge side of the deck and along the tapered portion thereof, the forward ends of the main riffles being laterally beveled to form channels between the same and the displacement riffles, the forward ends of the displacement riffles terminating in the diagonal line of the terminals of the main riffles.

In witness whereof we have hereunto subscribed our names this 6th day of September, 1919.

EMIL DEISTER.
WILLIAM F. DEISTER.
